6 Claims. (Cl. 57—58.89)

ABSTRACT OF THE DISCLOSURE

A device for guiding yarn which passes from the outlet of a rotary spinning chamber to a yarn take-up. The device comprises a guide member formed with an elongated yarn-conveying passage and this passage has an intermediate portion of smallest cross section and two outward portions located on opposite sides of the intermediate portion. Each of the outward portions has a cross section which increases in the direction away from the intermediate portion.

Background of the invention

The present invention relates to an improved yarn guiding device, and more specifically to a device for guiding yarn which passes from the outlet of a rotary spinning chamber to a yarn take-up. Still more specifically, the invention relates to such a yarn guiding device for guiding yarn from the spinning chamber of an apparatus used in the continuous ringless spinning of fibers.

It is known to feed into rotary spinning chambers a stream of substantially separated fibers which impinge against an inner circumferential surface of the spinning chamber and are deposited thereon in cohesive form as the result of the centrifugal force to which they are subjected upon impinging against the wall surface. The spinning chamber is provided with an outlet and the layer which is continuously being deposited on the wall surface is withdrawn through this outlet in form of a yarn. To guide the yarn during its movement out of the spinning chamber and through the outlet thereof it is known to provide a device known as a "funnel" which is formed with a passage of substantially constant cross section through which the yarn passes. However, these prior-art devices are possessed of certain disadvantages. Firstly, the yarn rubs against the wall surrounding the opening of substantially constant cross section, and secondly, the yarn also rubs against the edge at the inlet end of the yarn guiding passage, that is the end which communicates with the outlet of the spinning chamber. Obviously, in both cases the yarn is subjected to a certain amount of damage and it need not be specifically emphasized that this is highly undesirable. Furthermore, the use of these devices with known spinning chambers makes it very difficult to return the end of the yarn into the spinning chamber if a yarn breakage has occurred and if it is necessary to reprime, that is to reconnect the end of the yarn to the layer which has formed on the inner circumferential surface of the spinning chamber wall.

All of these are disadvantages which have long made it desirable to provide improvements in the state of this art. However, such improvements heretofore have not existed.

Summary of the invention

With the above comments in mind, it is a general object of the present invention to overcome the disadvantages of the prior art as set forth hereinbefore.

A more specific object of the invention is to provide a device for guiding yarn which passes from the outlet

2

of the rotary spinning chamber to a yarn take-up, and such a device is not to damage in any way the yarn passing therethrough.

An additional object of the invention is to provide such a device of the type set forth above which facilitates returning of the yarn end into the spinning chamber for the purpose of repriming.

In accordance with one feature of our invention we provide a device for guiding yarn which passes from the outlet of the rotary spinning chamber to a yarn take-up. Such device comprising a guide member having an elongated yarn-conveying passage therein. The passage has an intermediate portion of smallest cross section and it further comprises two outward portions which are located on opposite sides of the intermediate portion. Each of the outward portions has a cross section which increases in the direction away from the intermediate portion.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

Brief description of the drawing

The single figure is a somewhat schematic, partially sectioned elevational view of a device in accordance with the present invention.

Description of the preferred embodiment

Discussing now the drawing in detail it will be seen that reference numeral 4 identifies a rotary spinning chamber which rotates in the direction of the arrow. The spinning chamber 4 is provided with an internal circumferential collecting surface 3 and has an open end which is not identified with a separate reference numeral but is clearly evident. Spaced from this open end the spinning chamber 4 is provided in its circumferential wall with a plurality of orifices 5 and the purpose of these is to set up, during rotation of the chamber 4, a negative pressure within the chamber 4.

45 A channel or tube 2 extends into the open end of the chamber 4 and feeds a constant stream 1 of separated fibers into the interior of spinning chamber 4 so that these fibers impinge against the collecting surface 3. Under the influence of centrifugal force, to which they are subjected upon impinging against the collecting surface 3, the fibers of stream 1 form a relatively cohesive mass which is withdrawn from the collecting surface 3 in form of a yarn 6. A withdrawing device, which may consist of two nip rollers 9, one of which may be driven, is provided spaced from the outlet of the rotary spinning chamber 4 and downstream of this withdrawing device there is provided a yarn take-up, such as bobbin 10 onto which the yarn is wound.

In accordance with the invention the yarn is guided out of the open side of the spinning chamber 4 by a guiding device, namely the funnel 8. This funnel 8 is provided with a draw-off channel 7 extending the entire length of the funnel and having, as is clearly evident from the drawing, an intermediate portion of smallest cross section and two outward portions which are located on opposite sides of the intermediate portion. Each of these outward portions has a cross section which increases in the direction away from the intermediate portion as is also evident from the drawing. As shown, the yarn 6 being withdrawn from the collecting surface 3 of the rotary spinning chamber 4 is gently deflected by the innermost outward portion of the channel 7, that is the outward portion which is

located at or within the open side of the spinning chamber 4 and which converges in its cross section toward the portion of narrowest cross section. There is no pronounced edge against which the yarn 6 could rub and thereby be damaged, and there is only a relatively small or rather short wall portion over which the yarn 6 contacts the wall surrounding the passage 7. Once the yarn has passed through the portion of narrowest cross section of the passage 7 it passes into the other outward portion, that is the one which is located farther spaced from the spinning chamber 4, and it is evident from the drawing that there is now no further contact between the yarn 6 and the receding surface 11 of the wall which bounds that other outward portion of the channel 7.

Clearly, the construction here shown greatly reduces damage resulting from frictional contact between the yarn 6 and the funnel 8 and thus contributes significantly to a more efficient handling of the yarn.

However, this is by no means the only advantage of the construction in accordance with the present invention. As has been pointed out earlier, when the yarn 6 breaks its free end must be returned into the spinning chamber 4 so that it will contact again the collecting surface 3 and thus be linked up or connected to the fibrous mass which is being withdrawn therefrom so that the yarn will again be continuous. This process is known as repriming and the procedure therefore is known in the art. A detailed discussion of this procedure is therefore not believed to be necessary and it might merely be pointed out that the negative pressure existing in the interior of the rotary spinning chamber 4 helps to convey the returning yarn end into the interior of the chamber and into contact with the collecting surface 3 thereof. In accordance with the present invention the return of the free yarn end 6 into the spinning chamber 4 is aided by the fact that the outer one of the outward portions of channel 7, that is the one which is located closer to the withdrawing device 9, diverges in its cross section in the direction towards this withdrawing device. This may also be reversely stated by saying that its cross section decreases in the direction towards the spinning chamber so that the free end of the yarn 6, when such free end is being returned into the spinning chamber 4, is thus reliably guided by the converging surfaces 11 into the portion of narrowest cross section of the channel 7. From there, and by virtue of the fact that the cross section then again increases as seen in the direction of the returning movement of the free yarn end, the yarn will move along the diverging surface of the inner of the outward portions of channel 7 and will thereby be guided gently in the direction towards the collecting surface 3 for link-up with the fibrous mass forming thereon. This is assisted by the fact that the velocity of the carrier medium utilized in repriming increases as the cross section of the channel 7 decreases, as seen in the direction of the returning movement of the

free yarn end, so that the speed of the yarn end is accelerated and the yarn is straightened. Of course, this does not preclude the possibility that a suitable priming element or implement be additionally used or substituted, but in any case the advantage inherent in the novel construction, both for withdrawing of yarn and for returning of the yarn end for the purpose of repriming, will be clearly obvious.

It will be understood that each of the elements described above, or two or more together, may also find a useful application in other types of yarn guiding devices differing from the types described above.

While the invention has been illustrated and described as embodied in a yarn guiding device, it is not intended to be limited to the details shown, since various modifications and structural changes may be made without departing in any way from the spirit of the present invention.

What is claimed as new and desired to be protected by Letters Patent is set forth in the appended claims:

1. In a spinning device, in combination, a rotary spinning chamber having an outlet; and guide means for guiding yarn which passes from said guide means, comprising a guide member having an elongated yarn-conveying passage therein, said passage having an intermediate portion of smallest cross-section and two outward portions located on opposite sides of said intermediate portion and each having a cross-section which increases in the direction away from said intermediate portion, one of said outward portions being located in said spinning chamber and said intermediate portion being located within the confines of said outlet.

2. A device as defined in claim 1, wherein the cross-section of the other outward portion diverges conically.

3. A device as defined in claim 1, wherein the length of said one outward portion is considerably less than the length of the other outward portion.

4. A device as defined in claim 3, wherein the cross-section of said other outward portion diverges conically.

5. A device as defined in claim 4, wherein the cross-section of said one outward portion diverges at a greater angle than the cross-section of said other outward portion.

6. A device as defined in claim 1, wherein said passage extends substantially normal to the direction of rotation of said spinning chamber.
